CLAIM

The ornamental design for a battery connector kit, as shown and described.

DESCRIPTION

FIG. 1 is a first perspective view of a battery connector kit showing our new design;

FIG. 2 is a second perspective view thereof;

FIG. 3 is a front view thereof;

FIG. 4 is a back view thereof;

FIG. 5 is a left side view thereof;

FIG. 6 is a right side view thereof;

FIG. 7 is a top view thereof;

FIG. 8 is a bottom view thereof;

FIG. 9 is an exploded view of the battery connector kit thereof;

FIG. 10 is a second exploded view of the battery connector kit thereof; and,

FIG. 11 is a third exploded view of the battery connector kit thereof.

The broken lines shown in the drawings depict portions of the battery connector kit that form no part of the claimed design.
